Application July 21, 1953, Serial No. 369,456

8 Claims. (Cl. 53—291)

This invention relates to a device for applying tubular bands or sleeves to the necks of bottles for sealing the cap or cork of such bottles. More particularly, the invention relates to a device for feeding an elongated continuous ribbon of tubular material in flattened form for insertion around a bottle neck as distinguished from those devices which handle sleeves that have been previously cut to the required length before being fed to the bottle.

At present, it is customary to apply a tubular band or sleeve of plastic to filled bottles so that such band overlies the cap, cork or other closure and also a portion of the neck of the bottle. Aside from the enhanced attractiveness of the finished container, the band makes the container tamper proof as it is impossible to remove the closure without breaking or tearing the band.

The material of the band is a cellulose material, usually applied wet, which has the property of shrinking to a considerable extent upon drying. Prior to insertion on the bottle, the banding material is stored in a suitable liquid which prevents shrinking.

At present, the usual procedure is to apply the plastic bands or sleeves manually although several types of automatic devices have been proposed. The main disadvantage of such devices is their complexity and expensiveness and even the very large bottlers find it more economical to apply the bands manually than to incur the large initial and maintenance expense involved in the use of the automatic machinery now available.

One type of automatic machine now in use applies banding sleeves that have previously been cut to the desired length and which sleeves are stacked in magazines in flattened form. However, the difficulties attending the steps of removing the sleeves from the magazines, opening or expanding the flattened sleeves to tubular form and thereafter applying them to the bottles, necessitate the provision of intricate machinery, not only making the initial cost high, but presenting a maintenance problem of keeping the machine running smoothly. An example of the type of device which applies pre-cut sleeves may be seen in the patent to Allen et al., 2,579,458, dated December 25, 1951.

The preferable solution to the problem is to feed the banding material to the bottles in the form of a flattened ribbon and to sever the ribbon after a tubular portion of the same has been applied to the bottle neck. This method is found in the patent to Holstein, 2,623,673, dated December 30, 1952.

However, the continuous feeding of tubular material requires that a floating mandrel be provided within the tube for feeding the latter and also for expanding the same to cylindrical form for insertion around the bottle neck. Heretofore, no simple means has been provided for carrying out this method and, to applicants' knowledge, commercial utilization of this method has not been feasible because of the complexity of the devices at present available.

The main object of the present invention is, therefore, the provision of a device for applying tubular bands to

2

the necks of bottles and which device is economical to build and maintain, and may be substituted for the manual operation with a great savings in cost.

Another object of the invention is the provision of a commercially feasible device for applying tubular bands to bottles from a continuous ribbon of the banding material in flattened form.

Still another object of the invention is the provision of a floating mandrel of extremely simple construction having no moving parts thereon and over which the tubular banding material may be readily inserted by unskilled personnel.

Another object of the invention is to provide a floating mandrel which requires no external supporting means except a pair of feed rollers for holding the mandrel in operating position.

Other objects and advantages will be seen from the following specification and drawings.

Fig. 1 is a semi-schematic vertical cross sectional view through the banding machine showing bottles in the two positions in which the important operations of the machine are carried out.

Fig. 2 is a reduced isometric view of the floating mandrel.

Fig. 3 is an enlarged end elevational view of the feed rollers showing the same in feeding relationship with an elongated strip of the tubular banding material and showing the floating mandrel partially in section to show internal structure and with portions of the banding material broken away to show the action of the feed rollers.

Fig. 4 is a side elevational view of the apparatus of Fig. 3 with parts broken away for clarity.

Fig. 5 is a horizontal cross sectional view through the tubular portion of the plastic band showing the same in its expanded condition on the bottle neck.

In detail, the invention may be incorporated in a conventional turret type bottle conveyor which includes a vertically disposed center post 1 secured at its lower end by means of a base 2 to a suitable frame member generally designated 3. The frame 3 may include a top 4 and a plurality of legs 5 for spacing said top any desired distance off the floor (Fig. 1).

Surrounding post 1 and coaxial therewith is a rotating hollow post 7 which is rotatably supported at its lower end in base 2. The upper end of the stationary center post 1 is provided with a relatively large horizontally disposed bevel gear 8 to which said center post is rigidly secured as by welding. The upper end of the rotating post 7 is rotatably secured to the hub of gear 8. Adjacent the lower end of the rotating post 7, the same is provided with a relatively large spur gear 10 which is in mesh with a pinion 11 carried on the upper end of a vertical shaft 12 which passes downwardly through the top 4 of frame 3. The lower end of shaft 12 is driven through reducer 13 from a suitable motor 14.

Carried by rotating post 7 intermediate its ends is a horizontally disposed turntable 15 which is peripherally provided with upwardly and radially outwardly opening pockets 16 in the usual manner for receiving the bottles therein. Any desired number of pockets 16 may be provided.

Within each pocket 16 is a vertically reciprocable shaft 17 which carries at its upper end a horizontally disposed bottle supporting platform 18 on which an upright bottle 22 may be received. Carried by the lower end of each shaft 17 is a roller 19 which rests on a peripherally extending stationary cam track 20 which, in turn, is supported on top 4 of frame 3.

The cam track 20 is designed so as to raise the bottle 20 on platform 18 to an upper position at station A shown at the left of Fig. 1 and then to a lower position at station B to the right of Fig. 1. It will be understood that

stations A and B need not necessarily be 180 degrees apart, but they are shown as such for convenience. It will also be apparent that any one of many conventional means may be employed for feeding the bottles to the turntable and removing them after the desired operation has been performed.

Spaced above the upper end of the rotating post 7 is a reservoir 23 which is adapted to contain a quantity of liquid 24 such as alcohol, glycerine or whatever other liquid is employed to prevent premature shrinkage of the plastic banding material.

Reservoir 23 may be supported on a horizontally disposed plate 6 which in turn is supported by downwardly extending ears 25 secured at their lower ends, as by welding, to the upper end of rotating post 7.

As described above, the bevel gear 8 is stationarily secured to the fixed center post. Meshing with bevel gear 8 are a plurality of vertically disposed bevel gears 27 which are carried at the inner ends of radially extending shafts 28. Adjacent the gears 27, the shafts 28 are rotatably supported in ears 25. At its outer end, each shaft 28 is provided with the movable half 29 of a clutch generally designated 30. Coaxial with each shaft 28 and radially outwardly thereof is a stub shaft 31 which is rotatably supported in an ear 32 depending from the periphery of the plate 6. The inner end of each stub shaft 31 is provided with a fixed clutch half 33 which cooperates with the movable half 29 for transferring rotation from shaft 28 to shaft 31.

Between ear 32 and fixed clutch half 33 is a spur gear 35 secured to shaft 31 and in mesh with a similar spur gear 36 (Figs. 1, 3) on a shaft 37. Shaft 37 is also rotatably supported in ear 32.

Shafts 31, 37 extend outwardly in side by side parallel relationship beyond the periphery of plate 6 and are provided with cylindrical sleeves 38, 39 respectively (Fig. 3) of yieldable material such as soft rubber. As best seen in Fig. 3, the spacing between shafts 31, 37 and the thickness of sleeves 38, 39 is such that the latter are in rolling engagement at their line of contact. The shafts 31, 37 together with sleeves 38, 39 constitute feed rollers generally designated 40, 41 respectively.

Each stub shaft 31 is actuated through clutch 30 from shaft 28 which rotates constantly as long as post 7 is rotating. This is due to the coaction between the stationary bevel gear 8 and the rotatable bevel gear 27 on shaft 28. Clutch 30 is actuated by means of a toggle linkage generally designated 43 which includes a link 45 pivotally supported at one end to ear 25 on plate 6 and a link 46 pivotally supported at one end to the movable clutch half 29. Links 45, 46 are each pivotally connected at their other ends to the upper end of a vertically extending link 47 which in turn is pivotally secured to an elongated, generally horizontally disposed arm 48.

Arm 48 extends radially outwardly of the machine and is supported for vertical swinging at its inner end as at 49 to rotating post 7. The outer end of arm 48 is bifurcated to provide a yoke 49 (Fig. 5) which is adapted to rest on the shoulder 44 of the bottle on platform 18.

Upon upward movement of the bottle platform 18 to raise the bottle to the position of station A, it will be apparent that the clutch 30 will be engaged so as to transfer the rotary motion of shaft 28 to stub shaft 31 in the direction indicated, (Figs. 1, 3).

By the above described structure, it will be apparent that shafts 31, 37 rotate in the direction indicated so as to feed any material between the rollers defined by sleeves 38, 39 in a downward direction. This feeding action will, of course, continue until the clutch 30 is disengaged by downward movement of the bottle between stations A and B. It will be understood that the length of time during which the feeding action of the rollers 40, 41 takes place may be predetermined by forming cam track 20 to the desired shape. By making the arm 48 relatively long

and of sufficient weight, the clutch 30 is disengaged by gravity as the bottle is lowered.

Although the particular means for transferring the bottles from the usual straight conveyor to the turntable 15 is not shown herein because any conventional means may be employed, it will be understood that the bottles are inserted into and withdrawn from the turntable at an elevation corresponding to the lower position of the bottle shown at station B.

Within the reservoir 23 are a plurality of shafts 50 (only two being shown) each of which is adapted to receive a roll 51 of flexible plastic tubular banding material in flattened form so that said material may be pulled from the roll in an elongated flat ribbon. Adjacent the periphery of reservoir 23 a sheave or roller 52 is provided for each roll 51 so as to act as a fair lead for the ribbon 53 to permit reversing its direction so that the same may be fed downwardly between rollers 40, 41.

Before being engaged by feed rollers 40, 41 the ribbon 20 53 is threaded over a floating mandrel generally designated 55 (Figs. 1-4).

As best seen in Figs. 2-4, mandrel 55 comprises a generally inverted U-shaped portion of heavy wire comprising a pair of parallel side pieces 56, 57 connected together at their upper ends by a semi-circular portion 54.

Integral with the lower ends of side pieces 56, 57 is a support member 58 extending transversely between pieces 56, 57 and formed to provide a convex downwardly directed surface 59 which is adapted to rest on rollers 40, 41 adjacent to but spaced upwardly from their line of engagement (Fig. 3).

Integrally secured to the underside of support member 58 and in continuation of side pieces 56, 57 is a second pair of side pieces 60, 61 respectively; the length of which is about equal to the outer diameter of rollers 40, 41. Rigidly secured to the lower ends of side pieces 60, 61 is a forming die generally designated 62. Die 62 is bifurcated to provide a pair of upwardly divergent legs 63, 64 which are secured at their upper ends to the lower ends of side pieces 60, 61 respectively. The legs 66, 64 are formed with smooth convex outer surfaces and merge smoothly with a short cylindrical end portion 65.

As seen in Figs. 3, 4, the circumferential extent of the mandrel in cross section between support 59 and the cylindrical portion 65 is uniform for all sections and it will be seen that when the mandrel 55 is threaded over the flattened ribbon 53 and the latter is moved downwardly relative to the mandrel 55, the ribbon is gradually expanded to a substantially cylindrical form.

In operation, the ribbon 53 is directed downwardly from idler roller 52 (Fig. 1) and the mandrel 55 is threaded over the flattened ribbon 53 and the latter is moved downwardly relative to the mandrel 55, the ribbon is gradually expanded to a substantially cylindrical form. In operation, the ribbon 53 is directed downwardly from idler roller 52 (Fig. 1) and the mandrel 55 is threaded over the flattened ribbon 53 and the latter is moved downwardly relative to the mandrel 55, the ribbon is gradually expanded to a substantially cylindrical form. In operation, the ribbon 53 is directed downwardly from idler roller 52 (Fig. 1) and the mandrel 55 is threaded over the flattened ribbon 53 and the latter is moved downwardly relative to the mandrel 55, the ribbon is gradually expanded to a substantially cylindrical form. In operation, the ribbon 53 is directed downwardly from idler roller 52 (Fig. 1) and the mandrel 55 is threaded over the flattened ribbon 53 and the latter is moved downwardly relative to the mandrel 55, the ribbon is gradually expanded to a substantially cylindrical form.

As best seen in Fig. 3, the forming die 62 is formed with a downwardly opening central recess 70 which is adapted to receive therein the upper portion of the neck 72 of the bottle 22. The neck of the bottle 22 may be provided with a cork 71 or other closure in the usual manner.

Assuming that the expanded ribbon has been fed downwardly between the rollers 40, 41 so that its lower end projects a slight amount below the lower end of forming die 62, as seen at station A in Fig. 1, it will be apparent, upon upward movement of the bottle 22 caused by cam

track 20 the clutch 30 will be engaged and cause the rollers 40, 41 to feed the ribbon 53 downwardly to surround the neck of the bottle as seen in Fig. 3.

In this connection, it should be noted that the inner diameter of the tubular band which is applied to the bottle neck is larger than the outside diameter of the latter, so that a rather loose fit between band and bottle results. Although it will be understood that after shrinkage, an extremely tight fit is achieved. However, before such shrinkage occurs, the wet plastic band nevertheless tends to hug the sides of the bottle neck despite the loose fit. This tendency is enhanced because of the fact that the ribbon 53, being originally flattened, is provided with slight creases 75, 76 (Fig. 5) which make the cross sectional shape elliptical after the banding ribbon becomes free from the forming die 62. This particular configuration of the ribbon prevents the band from dropping downwardly onto shoulder 44 of the bottle 22 after a portion of the ribbon has been severed to form a sleeve.

As described earlier, the amount of ribbon fed onto each bottle, which determines the length of the finished sleeve, depends upon the configuration of the cam track 20 as the latter determines the length of time that the bottle remains in the raised position.

After a predetermined length of band has been fed around the bottle neck, feeding stops and the bottle 22 is moved to station B at which point the track 20 is provided with a horizontal portion 78 which prevents vertical movement of the bottle. During the time the bottle 22 is being lowered to station B, it will be moving downwardly away from the ribbon 53 so that a space is formed between the closure 71 of the bottle and the bottom of the forming die 62 of mandrel 55 (Fig. 1).

Alongside station B is a vertically extending elongated shaft 80 which is rotatably supported at its upper end in a bearing 81 secured to any suitable adjacent structure. The shaft 80 is rotatably supported at its lower end in a bearing 82 fixed to one of the legs 5 of frame 3 and is provided at its lower end with a bevel gear 83 in mesh with a similar bevel gear 84 carried by a horizontal shaft 85. Shaft 85 may be an extension of the armature shaft of motor 14 and a bearing 86 may be provided for the same on frame 3.

The upper end of shaft 80 is secured to a conventional disc knife 87 which is constantly rotating with shaft 80. Knife 87 is positioned with its cutting edge in the space between the top of the bottle and the forming die 62 so that as the bottle 22 is carried past station B the ribbon is automatically severed so as to leave a sleeve 88 on the top of the bottle neck.

It is extremely important to note the particular configuration of the mandrel 55 and that the transverse support 58 is the only means for supporting the mandrel. Although the support 58 is actually supported on the rollers 40, 41 it is not in engagement with the same inasmuch as the opposite sides of the ribbon 53 are interposed between the support 58 and the rotating rollers 40, 41.

The fact that the ribbon 53 is wet during the above described operation reduces the friction between support 58 and the sidewalls of the ribbon and causes the mandrel to float freely on the rotating rollers. However, the wet condition of the ribbon also reduces the traction between the rollers and the ribbon but a positive feeding effect is achieved by making the ribbon engaging sleeves of relatively soft pliable rubber. If desired, the traction may be enhanced by forming ridges or ribs on the rollers, but this is not required, it being preferable not to mar the surface of the plastic ribbon by such means.

The mandrel 55 is stable in an upright position because the forming die 62 is substantially heavier than the upper portion of the mandrel. For this reason the mandrel is truly a floating one inasmuch as only gravity acts upon it to keep it upright in operating position. If desired, the forming die 62 may be made hollow but it

should be of sufficient weight to make the mandrel stable.

We claim:

1. In a banding machine, a feeding mechanism for downwardly feeding a vertically extending ribbon of flattened flexible tubular material comprising: a pair of horizontally disposed feed rollers in side by side relationship and respectively adapted to frictionally engage the opposite outer sides of said ribbon during feeding thereof between said rollers with said ribbon flattened, means for rotating said rollers oppositely with their adjacent surfaces moving in the direction of feed of said ribbon for so feeding the latter, a floating mandrel adapted to be received within said ribbon, a support on said mandrel supporting the latter at corresponding points on said rollers with the sides of said ribbon interposed between said support and said rollers, a forming die on said mandrel on the opposite side of said rollers from said support for expanding said ribbon during feeding thereof to a generally tubular portion for receiving a bottle neck therein, and means for connecting said portion and said die.
2. In a banding machine, a feeding mechanism for downwardly feeding a vertically extending ribbon of flattened flexible tubular material comprising: a pair of horizontally disposed feed rollers in side by side relationship and respectively adapted to frictionally engage the opposite outer sides of said ribbon during feeding thereof between said rollers with said ribbon flattened, means for rotating said rollers oppositely with their adjacent surfaces moving in the direction of feed of said ribbon for so feeding the latter, a floating mandrel adapted to be received within said ribbon, a support on said mandrel supporting the latter at corresponding points on said rollers with the sides of said ribbon interposed between said support and said rollers, a forming die on said mandrel on the opposite side of said rollers from said support for expanding said ribbon during feeding thereof to a generally tubular portion for receiving a bottle neck therein, and means for connecting said support and said die, said forming die being integral with said mandrel and relatively heavy for maintaining said mandrel in an upright position.
3. In a banding machine, a feeding mechanism for downwardly feeding a vertically extending ribbon of flattened flexible tubular material comprising: a pair of horizontally disposed feed rollers in side by side relationship and respectively adapted to frictionally engage the opposite outer sides of said flattened ribbon centrally of the latter during feeding thereof between said rollers, said rollers having similar ribbon engaging surfaces having a horizontal extent less than the width of said ribbon whereby the opposite vertically extending marginal portions of said ribbon are free from engagement by said rollers, a floating mandrel adapted to be received within said ribbon and provided with a support for supporting the same on the upper sides of said rollers with the sides of said ribbon interposed between said support and said rollers, a forming die on said mandrel and below said rollers for expanding said ribbon during feeding thereof to a generally cylindrical form for receiving the top of a bottle neck therein, a pair of vertically extending elongated elements connecting said support and said die, and received within said marginal portions of said ribbon.
4. In a banding machine, a feeding mechanism for downwardly feeding a vertically extending ribbon of flattened flexible tubular material comprising: a pair of horizontally disposed feed rollers in side by side relationship and respectively adapted to frictionally engage the opposite outer sides of said flattened ribbon centrally of the latter during feeding thereof between said rollers, said rollers having similar ribbon engaging surfaces having a horizontal extent less than the width of said ribbon whereby the opposite vertically extending marginal portions of said ribbon are free from engagement by said rollers, a floating mandrel adapted to be received within said ribbon and provided with a support for supporting

the same on the upper sides of said rollers with the sides of said ribbon interposed between said support and said rollers, a forming die on said mandrel and below said rollers for expanding said ribbon during feeding thereof to a generally cylindrical form for receiving the top of a bottle neck therein, a pair of vertically extending elongated elements connecting said support and said die, and received within said marginal portions of said ribbon, said forming die being relatively heavy for automatically maintaining said mandrel in an upright position.

5. In a banding machine, a feeding mechanism for downwardly feeding a vertically extending ribbon of flattened flexible tubular material comprising: a pair of horizontally disposed feed rollers in side by side relationship and respectively adapted to frictionally engage the opposite outer sides of said flattened ribbon during feeding thereof between said rollers, means for rotating said rollers oppositely with their adjacent surfaces moving in the direction of feed of said ribbon for so feeding the latter, a floating mandrel adapted to be received within said ribbon, a support on said mandrel supporting the latter at corresponding points on said rollers with the sides of said ribbon interposed between said support and said rollers, a forming die on said mandrel on the opposite side of said rollers from said support for expanding said ribbon during feeding thereof to a generally tubular portion for receiving a bottle neck therein, means for connecting said support and said die, a bottle support for supporting a bottle upright and coaxial with said die, means for moving such bottle toward said die for so receiving said tubular portion around the bottle neck, and means for severing said portion at a point between the top of said bottle and said die.

6. A mandrel adapted for use with a ribbon of flattened flexible tubular material adapted to be fed in tubular form onto the neck of a bottle, said mandrel comprising: a support portion extending transversely of said mandrel and adapted to be supported on a pair of parallel rollers with such ribbon flattened between said rollers, a die portion longitudinally spaced from said support portion and adapted to expand such flattened ribbon to a tubular

shape, said longitudinal spacing between said support portion and said die portion providing an opening for receiving said flattened ribbon therein with said rollers engaging the opposite outer sides of said ribbon.

5. 7. A mandrel adapted for use with a ribbon of flattened flexible tubular material adapted to be fed in tubular form onto the neck of a bottle, said mandrel comprising: a support portion extending transversely of said mandrel and adapted to be supported on a pair of parallel rollers with such ribbon flattened between said rollers, a die portion longitudinally spaced from said support portion and adapted to expand such flattened ribbon to a tubular

10 shape, said longitudinal spacing between said support portion and said die portion providing an opening for receiving said flattened ribbon therein with said rollers engaging the opposite outer sides of said ribbon, said mandrel being unitary with said portions integrally secured together.

15 8. A mandrel adapted for use with a ribbon of flattened flexible tubular material adapted to be fed in tubular form onto the neck of a bottle, said mandrel comprising: a support portion extending transversely of said mandrel and adapted to be supported on a pair of parallel rollers with such ribbon flattened between said rollers, a die portion longitudinally spaced from said support portion and adapted to expand such flattened ribbon to a tubular

20 shape, said longitudinal spacing between said support portion and said die portion providing an opening for receiving said flattened ribbon therein with said rollers engaging the opposite outer sides of said ribbon, said mandrel being unitary with said portions integrally secured together.

25 9. A mandrel adapted for use with a ribbon of flattened flexible tubular material adapted to be fed in tubular form onto the neck of a bottle, said mandrel comprising: a support portion extending transversely of said mandrel and adapted to be supported on a pair of parallel rollers with such ribbon flattened between said rollers, a die portion longitudinally spaced from said support portion and adapted to expand such flattened ribbon to a tubular

30 shape, said longitudinal spacing between said support portion and said die portion providing an opening for receiving said flattened ribbon therein with said rollers engaging the opposite outer sides of said ribbon, said mandrel being unitary with said portions integrally secured together, with said die portion relatively heavy to maintain said mandrel in an upright position when said

35 rollers are horizontal.
